UNITED STATES PATENT OFFICE.

GEORGE JOHN WALDVOGEL, OF TOLEDO, OHIO.

DESIGN FOR A MUSIC-STOOL.

SPECIFICATION forming part of Design No. 23,424, dated July 3, 1894.

Application filed April 13, 1893. Serial No. 470,248. Term of patent 7 years.

To all whom it may concern:

Be it known that I, GEORGE JOHN WALDVOGEL, of Toledo, county of Lucas, and State of Ohio, have invented a new and original Design for Music-Stools; and I do hereby declare that the following is a full, clear, and exact description thereof, which will enable others skilled in the art to which it appertains to make and use the same, reference being had to the accompanying drawing, and to the numerals of reference marked thereon, which form part of this specification.

My invention pertains to a new and original design for music stools, and applies more particularly to the base support.

The leading features of my design consist in a stool having a base support comprising leg supports in the form of a lyre.

In the drawing, the figure is a perspective view of a music stool constructed in accordance with my design.

1 designates the base support comprising

frames 2, set at an angle to each other, each frame having the shape of a lyre in which are vertical posts 3, which correspond to and represent the strings. The frames 2 serve as supports for legs 4, which are connected therewith. The lyre frames are joined to a central post 5, which supports the seat 6.

The ornamentation of the sustaining portion of the seat by the frames and posts in representation of a lyre is at once pleasing and appropriately suggestive.

What I claim is—

The design for a music stool as herein shown and described.

In testimony that I claim the foregoing as my own I hereby affix my signature in presence of two witnesses.

GEORGE JOHN WALDVOGEL.
